Selden A. Bailey
By F. C. Jones,
Attorney.

UNITED STATES PATENT OFFICE.

SELDEN A. BAILEY, OF NEW LONDON, CONNECTICUT.

VEHICLE-SPRING.

SPECIFICATION forming part of Letters Patent No. 357,753, dated February 15, 1887.

Application filed February 16, 1886. Serial No. 192,083. (No model.)

To all whom it may concern:

Be it known that I, SELDEN A. BAILEY, a citizen of the United States, residing at New London, in the county of New London, State 5 of Connecticut, have invented certain new and useful Improvements in Vehicle-Gears, of which the following is a specification, reference being had therein to the accompanying drawings.

10 The object of this invention is to provide an improved vehicle-gear which combines the properties of simplicity, economy, and strength of construction with lightness and symmetry, and which will cause the vehicle to ride easy 15 and steady whether under a light or a heavy load.

Figure I is a rear elevation of this improved vehicle-gear, wherein a straight hind axle is used, the vehicle-body being indicated by dotted lines. Fig. II is a perspective view of 20 this improved vehicle-gear, in which both the forward and hind axles are crank-axes, the vehicle being indicated by dotted lines.

Similar numerals of reference indicate corresponding parts in both figures.

The front axle, 1, is a crank-axe, and the hind axle, 2, may be either straight or cranked, preferably the latter. The crank-axe comprises a depressed central portion, 3, curved 30 portions 4, axle-shanks 5, and axle-spindles 6. A truss-bar, 7, comprising a steel plate, 8, and a wooden bar, 9, said plate and bar being clipped together, is disposed over the front axle in the same vertical plane therewith, being connected at its outer ends to curved 35 spring-brackets 10, which are clipped to said axle. In this construction the bar imparts the weight of the load at points near the wheel.

The lower half of a fifth-wheel, 11, is attached to the supporting-bar 7, and the other half thereof is attached to a semi-elliptic spring, 12, which curves upward from the center of said bar. The hind axle, 2, is connected with the upper half of the fifth-wheel 45 11, or with the semi-elliptic spring 12, by means of reaches 13, the rear ends of which are clipped to the rear axle. Braces 14 extend from said reaches to the rear axle.

The springs for supporting the vehicle-body 50 comprise, respectively, a semi-elliptic member, 12, in connection with two quarter-elliptic members, 15, which cross each other near their centers, the lower end thereof being con-

nected to the semi-elliptic member and their upper ends attached to the vehicle-body. The 55 quarter-elliptic members may be attached to spring-brackets 18 on the axle, and are reinforced by plate-spring cushions 16. These spring-cushions curve downward and are in contact with the quarter-elliptic members a 60 greater or less distance, according to the weight of the load, and serve to strengthen or stiffen said members under a heavy load and permit them to yield readily under a light load. The quarter-elliptic members and 65 the spring-cushions are provided with corresponding concavo-convex ribs, 17, and interlock with each other at points where they are attached to the vehicle-body.

The crossing quarter-elliptic members, in 70 connection with a semi-elliptic member, with the spring-brackets, and in further connection with the bow-shaped spring-cushions, constitute a spring that is very elastic under a light load, which has the requisite stiffness 75 for a very heavy load, and which has great capacity of self-adjustment to suit the varying weights put upon it. This spring is especially adapted for use as a substitute for the common elliptic spring, and the semi-elliptic 80 member thereof, which takes the place of the lower member of the ordinary elliptic spring, can be made shorter, and consequently may be composed of a less number of leaves than the lower member of an elliptic spring of the 85 same capacity and elasticity; hence this spring is more economical to make and is more compact and symmetrical.

I claim as my invention—

1. The combination, with a vehicle-spring 90 comprising two crossing quarter-elliptic members attached to a spring or spring-bracket on the axle and inclined in opposite directions, of two crossing bow-shaped spring-cushions having a variable contact with said members, 95 substantially as described.

2. The combination, with a crank-axe, of the spring-brackets 10, the truss-bar 7, connected at its opposite ends with said brackets, the spring 12, the crossing quarter-elliptic 100 members 15, and the fifth-wheel, substantially as described.

SELDEN A. BAILEY.
